DOOR LATCH MECHANISM

Kermit M. Sletten, Willmar, Minn.

Application September 30, 1937, Serial No. 166,523

5 Claims. (Cl. 292—336)

My invention relates to an improvement in a door latch mechanism of a type particularly designed for use on vehicle doors and the like.

It has been common practice in vehicle construction to provide door latches having a reciprocable latch member having a cam shaped end which engages a keeper on the door frame to hold the door in closed position. In view of the fact that the frame of a vehicle often springs out of proper position to a certain extent, deforming the body, the keepers of such latches are ordinarily provided with a double latch so that the door will not come open until the latch bolt has passed both portions of the keeper. This is to prevent the action of the vehicle in travelling over a bump from freeing the latch momentarily and permitting the door to swing open. It is also to permit the door to be latched shut even though the body has sprung sufficiently so that the door cannot be closed tightly.

It is a purpose of my invention to provide a latch mechanism which may be used upon vehicles and which will be tightened by jarring or vibration. Thus if the door is not entirely closed due to warping or deformation of the vehicle, the movement of the car will cause the latch to engage more tightly and to thus hold the door closed more securely. The present invention is a modification of my prior construction disclosed in application for Door latches, Serial No. 153,123, filed July 12, 1937.

It is a purpose of my invention to provide a latch in the form of a rotatable cam which may pivot into position to lock the door to the frame. This cam is preferably a segment of a screw thread and is urged into door engaging position by means of a suitable spring. The angle of the thread is such that transverse force acting against the cam cannot rotate the cam so that vibration of the vehicle can only act to tighten the cam in the keeper.

It is a feature of my invention to provide a door latch construction in which the door may be opened or closed with the least amount of resistance. Where the usual type of reciprocable bolt having a cam end is employed some force is usually required to force this bolt inwardly to permit the door to latch properly. For this reason it has been necessary to slam the vehicle door or to close the same quickly in order that the latch bolt be reciprocated inwardly to pass the keeper. It is a purpose of the present invention to provide a rotatable latch device which is held from rotation by means of a suitable trigger which is released when the door reaches closed

position, so that the rotary latch is released when closed position of the door is attained. As the trigger mechanism is much more easily operated than is the bolt of the usual type of lock, this construction enables the door to be closed much more easily than the constructions where the ordinary type of lock is employed.

It is a purpose of the present invention to provide a latch in the form of a rotary segment which is held in one extreme position by a pawl or dog, engaging in one of a series of notches in the rotatable member. The rotatable member is urged toward the other extreme position by means of a suitably positioned spring. The series of notches, engageable with the pawl or dog, ascertains that the cam remain in inoperative position and will not rotate into keeper engaging position when out of engagement with the keeper.

It is the purpose of the present invention to provide a latch bolt which is held in inoperative position by means of a trigger equipped with an operating cam. This cam is operated by engagement with the door frame and when the door reaches proper position within the frame, the trigger mechanism releases the latch bolt and permits the same to engage the keeper.

It is a further object of my invention to provide a latch mechanism which is virtually entirely contained within the body of the door and which is provided merely with a small cam extending from the door. Thus with my novel construction, it is virtually impossible to catch and tear the clothes in the manner of the latch bolt of the ordinary type of lock.

These and other objects and novel features of my invention will be more clearly and fully set forth in the following specification and claims.

In the drawing forming a part of my specification:

Figure 1 is a top plan view of my door latch in inoperative position.

Figure 2 is a cross-sectional view on the line 2—2 of Figure 1, illustrating the latch bolt.

Figure 3 is a view similar to Figure 2, illustrating the latch bolt in a different position.

Figure 4 is a transverse cross-sectional view horizontally through the center of the shaft handle of the latch mechanism, illustrated in Figures 1, 2, and 3.

Figure 5 is a perspective view of the latch mechanism.

Figure 6 is a view of the spring which operates the vehicle handle and holds the handle normally in one position.

My latch mechanism A includes a handle 10 of

55

the usual type used on vehicles and the like. The handle 10 is provided with an external portion 11 of relatively large diameter, a shank 12, or portion of reduced diameter, and a squared portion 13 at the end of the shank 12. The handle 10 extends through the side flange 14 of the latch frame 15 and extends through a sleeve 16. The shoulder 17 formed by the reduction in diameter of the shank 12 from the external portion 11, bears against the side flange 14 to properly position the handle 10 with respect to the latch mechanism frame 15.

A segment 19 is formed integral with the sleeve 16. This segment 19 as best illustrated in Figure 1 of the drawing is a segment of a gear thread, or in any event the periphery of the segment or cam 19 is helical with respect to the handle 10. A gear segment 20 is also provided integral with the sleeve 16 for engagement with the segment 21. The segment 21 is pivoted at 22 illustrated in Figure 2 of the drawing, and this segment is urged into one extreme position by the spring 23. The spring 23 tends to rotate the cam or segment 19 into engagement with the keeper 24. Accordingly, a constant pressure is provided tending to rotate the cam 19 into position to close the door tightly.

I provide a trigger mechanism for holding the cam or segment 19 out of keeper engaging position. This mechanism comprises a pawl or dog 25 which engages in one of a series of parallel notches 26 in the peripheral edge of the cam or segment 19. When the dog 25 is in engagement with one of the notches 26, the cam 19 is prevented from moving in the direction in which it is urged by the spring 23.

The dog or pawl 25 is mounted upon a transverse shaft 27 mounted between spaced bearings 29 and 30. The pawl or dog 25 is secured for rotation with the shaft 27 between the bearings 29 and 30 and a downwardly extending arm 31 is also similarly mounted on this shaft 27. At the lower extremity 32 of the arm 31, I provide a cam shaped element 33 which is engageable with the frame 34 of the vehicle B. In Figure 1 of the drawing, the cam 33 is illustrated in full lines while in dotted lines in this same view is illustrated the cam 33 forced inwardly by the vehicle door frame 34 to release the bolt 19. A spring 35 is provided between the frame 15 of the latch mechanism and the arm 31.

From the foregoing description it will be clear that if the cam 19 is in the position illustrated in full lines in Figures 1, 2, and 5 of the drawing, and the door upon which the latch is mounted is closed against the frame 34 of the vehicle B, the cam end 33 will be pivoted against tension of the spring 35 so that the arm 31 swings inwardly rotating the shaft 27 and pivoting the pawl or dog 25 to release the cam 19, whereupon this cam is free to pivot by action of the spring 23 into the closed position illustrated in dotted outline in Figure 1 and shown in Figure 3 of the drawing.

As was previously described, the handle 10 is not directly connected to the sleeve 16 to operate this sleeve. The squared portion 13 of the handle 10 is provided with a square bushing 36, which bushing is equipped with a substantially radially extending arm 37. This arm 37 is urged upwardly by a spring 39. Stop lugs 40 are formed in the side flange 14 of the frame 15 to limit the movement of the bushing 36 in each direction. This arm 37 engages the semi-circular flange 42 on the end of the sleeve 16. Rotation of the handle 10 can only occur when the handle is in normal position and the arm 37 is in the full line position illustrated in Figure 6. The arm 37 may only pivot in a clockwise direction from the position illustrated in full lines in Figure 6 to the position illustrated by dotted outline in this same figure. When the cam 19 is in the position illustrated in dotted outline in Figure 6 of the drawing, the latch bolt 19 cannot be operated by the handle 10, as this bolt is already in retracted position. However, when movement of the door containing the latch mechanism into engagement with the door frame 34 causes the cam 33 to release the pawl or dog 25, the cam 19 rotates into the position illustrated in Figure 3 of the drawing, bringing the edge 43 into engagement with the operating surface 44 of the arm 37. When the handle 10 is then rotated to turn the shaft of Figure 6 in a clockwise direction, the surface 44 of the arm 37 which rotates with the handle 10 will engage the end 43 of the flange 42 and permit rotation of the sleeve 16 into the position illustrated in Figure 6. When the sleeve 16 reaches this position, the latch bolt 19 or cam is removed from the keeper 24 and the door may be swung open. As the door is swung open, the cam 33 disengages from the door frame and the pawl or dog 25 engages one of the notches 26 in the periphery of the cam 19. As soon as the handle 10 is released the spring 39 rotates the handle in a counter-clock-wise direction, moving the handle into normal position. This construction enables the handle of the door to remain in normal position at all times when it is not being used, whether the cam is in locking position or is in open position.

The cam segment is held in inoperative position by the pawl or dog and the cam trigger which operates this pawl or dog may be seen from an observation of the drawing. The latch bolt or cam is not released until the door is virtually entirely closed and it may be seen that vibration tending to move the cam 19 will cause this cam to be moved more securely into engagement with the keeper, being urged in this direction at all times by the spring 23.

The manner in which the lock is actuated by an operating handle on the inside of the door is not illustrated in the drawing. It is believed only necessary to point out that the handle on the inside of the door operates the gear 21 pivoted at 22 in a manner well known in the art.

In accordance with the patent statutes I have described the principles of construction of my door latch mechanism and while I have endeavored to set forth the best embodiment thereof, I desire to have it understood that this is only illustrative of a means of carrying out my invention, and that obvious changes may be made within the scope of the following claims without departing from the spirit of my invention.

I claim:

1. A door lock comprising a door handle, a sleeve on said handle and rotatable with respect thereto, a latch cam on said sleeve, means for rotating said sleeve in a direction to rotate said cam into locking position, said handle remaining stationary, means on said handle engageable with said sleeve for pivoting said sleeve out of locking position, a series of notches in the periphery of said cam, and trigger means engageable in one of said notches, said trigger means

being operated by engagement with a door frame to disengage said notch to permit rotation of said bolt.

2. A door lock comprising a handle, a sleeve rotatable on said handle, a locking cam on said sleeve, spring means urging said sleeve into locking position, a notch in the periphery of said cam, and trigger means engageable in said notch to hold said cam from rotation, said trigger means including a dog engageable in said notch, a pivot extending parallel to said handle supporting said dog, and means engageable with a door frame to actuate said pivot.

3. A door lock comprising a door handle mechanism comprising a shank and a means urging said shank into one position; a sleeve on said shank, a cam on said sleeve, spring means urging said sleeve in one direction while said handle mechanism remains stationary, shoulder means forming a part of said handle mechanism for rotating said sleeve in the opposite direction, and trigger means for holding said cam in unlocked position, said trigger means including a pivot, door frame engaging means for operating said pivot, and dog means operated by said pivot.

4. A door lock comprising a handle mechanism including a shank rotatable between two extreme positions, and a means urging said

shank into one extreme position; a sleeve on said shank, means for rotating said sleeve in one direction while said handle remains stationary, a locking cam on said sleeve, means forming a part of said handle mechanism for rotating said sleeve in the opposite direction, a dog engageable with said cam, spring means urging said dog into engagement with said cam to hold said cam in unlocked position, a dog supporting pivot, and cam means engageable with the door frame to rotate said pivot to swing said dog out of engagement with said cam to release said cam to move under spring tension into locking position.

5. A door lock comprising a handle mechanism including a handle shank and a means normally holding said handle shank in one position; a sleeve mounted freely rotatable upon said shank, means urging said sleeve in one direction, means forming a part of said handle mechanism and engageable with said sleeve for moving said sleeve in the opposite direction, locking means on said sleeve, trigger means engageable with said locking means for holding said locking means in unlocked position, and means engageable with a door frame when the door is closed to release said trigger means.
